United States Patent

Des. 240,199
Patented June 8, 1976

240,199

PACKAGING TRAY

Alan J. Perfect, Allentown, N.J., assignor to
Johnson & Johnson, New Brunswick, N.J.

Filed Dec. 20, 1974, Ser. No. 534,612

Term of patent 14 years

Int. Cl. D9—03

U.S. Cl. D9—185

FIG. 1 is a top perspective view of a packaging tray showing my new design;

FIG. 2 is a bottom plan view;

FIG. 3 is a side elevational view looking in the direction of the arrow 3 of FIG. 1; and

FIG. 4 is an end elevational view looking in the direction of the arrow 4 of FIG. 1.

I claim:

The ornamental design for a packaging tray, as shown.
